UNITED STATES PATENT OFFICE.

HENRY E. AMOORE, OF YOKOHAMA, JAPAN.

POCKET HAND-WARMER.

SPECIFICATION forming part of Letters Patent No. 366,709, dated July 19, 1887.

Application filed December 3, 1886. Serial No. 220,623. (Model.)

To all whom it may concern:

Be it known that I, HENRY E. AMOORE, a subject of the Queen of Great Britain, residing at Yokohama, in the Empire of Japan, have invented a new and useful Pocket Hand-Warmer, of which the following is a specification.

My invention relates to portable warmers for the hands, and for other purposes where it is desired to place a heated body in contact with the object to be warmed, or in its vicinity, or to increase the heat of the surrounding atmosphere.

The object of the invention is, first, to provide a warmer which can be conveniently carried about the person or applied to any part of the person where a local application of heat is required; second, to construct the warmer so that it can be placed in any position without liability of the ashes or dust siftng through the air-holes; third, to produce a fuel which will burn freely, produce a gentle but steady heat, emit no unpleasant odors, and can be conveniently carried about and handled.

In the accompanying drawings, Figure 1 represents a side elevation of my improved hand-warmer; Fig. 2, a top view of the same; Fig. 3, a longitudinal vertical section of the warmer; Fig. 4, a cross section; Fig. 5, a plan of the under side of the cover; and Fig. 6 represents the fuel cartridge or stick.

Referring to the drawings, A represents the case of the warmer, which is made of sheet metal, and in a general rectangular form when viewed in front elevation; but it may be made in any suitable shape to adapt it to any special use. The top edge of the case is provided with a groove, a, which extends entirely around one end, but is terminated a short distance from the opposite end on both sides, as indicated at b b, and from these points the end and adjacent sides of the box or case are cut down to a depth below the bottom of the groove a equal to the thickness of a semi-elliptical plate, d, which is soldered to the top edges of the case, where they are cut down, as above stated, so that its upper surface lies flush with the bottom of the groove a. The cover B of the box is convex in the center, with projecting horizontal flanges e, which run in the groove a, and thus connect the cover with the box. At one

end of the cover a plate, f, of the same shape as plate d, is soldered to the under or concave side. When the cover is placed on the box or case, the plate f slides over the plate d, and thus a tight joint is formed, which prevents the ashes and dust from escaping at this point. The joint is made still tighter by means of a piece of fabric, g, which is pasted or otherwise fastened to the plate f, and which projects outside of the cover when closed, forming thus, in addition to packing the joint, a handle or tab by which the cover can be conveniently drawn off.

The sides and ends of the box or case are provided with numerous small perforations, h, which serve as air-holes or draft-openings for the entrance of air to the interior to support combustion. The top or cover is provided with similar openings, h'.

The box or case is covered or incased in a covering or casing, D, of cotton cloth, muslin, or other suitable fabric, and the top or cover is lined with a similar material. The object of this covering and lining is to stop or cover the draft-openings in such a manner that while an ample supply of air will be admitted to the burning fuel, at the same time the ashes and dust resulting from combustion will not be permitted to sift or escape through the perforations. The fabric does not close the openings sufficiently to shut out the air. The top or cover B is also lined with a similar fabric, k.

The fuel used in this device is composed of charcoal, which may be made from hemp, grass, wood, &c., and saltpeter and alum mixed together, or wood-charcoal mixed with saltpeter and alum, or either one of the latter ingredients alone; but I do not limit myself to the fuel composed of said ingredients, as any slow-burning smokeless and odorless fuel will answer that ignites and burns easily and steadily.

The fuel E, used in these warmers, is put up in paper cylinders l, forming cartridges or sticks F, a trifle less in length and width than the interior dimensions of the box or case. The fuel is composed of charcoal and certain ingredients designed and selected to maintain combustion, but at the same time prevent it from being too rapid. The charcoal, too, is made from peculiar materials.

The manner of using the warmer is as fol-

lows: The fuel-cartridges may be carried in the box or case, or in a separate receptacle. When the warmer is to be used, one of the cartridges is taken out and lighted at one end, 5 (preferably at the end where the paper is gathered in and tied,) and then replaced in the box. When well lighted, cover the box. If the application is to be local, place the box on the place where heat is required; but if it is to 10 be used for warming the hands it may be placed in the pocket or carried in the hand.

If the fuel should not burn as freely as desired, leave the cover partly open for a few moments, when the exposure will have the desired effect. 15

The warmer may either be carried in the hand or pocket, as stated, or it may be carried in any other convenient way that may be found beneficial. It can also be used for a local application of heat in cases of pain in the stomach, neuralgia, &c.; and for convenience it can be inserted or carried in a bag or other suitable receptacle of cotton-flannel or other material, for the purpose of avoiding the spilling of the charcoal, or the ashes and dust resulting from combustion. 20

I do not confine myself to the manner of applying the cover herein described, nor to the use of a fabric to close the draft openings. 25 Wire-gauze may, for example, be substituted for the cotton cloth.

I claim—

1. A pocket hand-warmer consisting of a receptacle for the fuel, composed of a metal

box the sides of which are provided with perforations and having a casing of cloth covering the said perforations, and a suitable cover, substantially as specified. 35

2. The combination of a metal box having perforated sides covered by or incased in a textile material, and the sides provided with a groove, *a*, with a cover which is provided with perforations covered by a lining of textile material, said cover being held in the groove in the sides of the box and sliding 40 45 therein, substantially as specified.

3. The combination of the metal box provided with a groove, *a*, and the plate *d*, fixed to the sides at one end of the box and flush with the bottom of the groove *a*, and the cover 50 *B*, provided at one end with a plate, *f*, which, when the cover is closed, slides over and rests on the plate *d*, substantially as specified.

4. The combination of the box provided with perforated sides and a suitable cover, the box being covered with a suitable textile fabric and the cover lined with the same, and a fuel-stick composed of a suitable powdered or triturated fuel inclosed in a case or cylinder of paper, substantially as specified. 55

In testimony that I claim the foregoing improved hand-warmer as my invention I have hereunto set my hand, at Yokohama, Japan, this 29th day of October, in the year 1886.

H. E. AMOORE.

In presence of—

G. H. SCIDMORE,
N. KUMAGAYA.
